UNITED STATES PATENT OFFICE.

ANDRE EUGENE BLONDEL, OF PARIS, FRANCE.

RECORDING APPARATUS FOR RADIOTELEGRAPHIC SIGNALS.

1,400,517.

Specification of Letters Patent. Patented Dec. 20, 1921.

Application filed April 26, 1919. Serial No. 293,003.

To all whom it may concern:

Be it known that I, ANDRÉ E. BLONDEL, a citizen of the Republic of France, residing at 41 Avenue de la Bourdonnais, Paris, in the Republic of France, have invented certain new and useful Improvements in Recording Apparatus for Radiotelegraphic Signals, (for which I have filed application in France, April 4, 1918,) of which the following is a specification.

In French Patent No. 451614, of the 9th December, 1912, and in the various additions thereto, the use is indicated of galvanometers or oscillographs of resonance having a variable characteristic period, which are adjusted to resonance with alternating currents of any frequency, by varying the tension in the wires of the bifilar suspension.

It was also indicated, in the said main French patent, in paragraph 4, that this apparatus could be utilized for the purpose of effecting the selection of radio-telegraphic waves, either by creating for the latter a certain periodic rhythm by producing them by means of alternators or by means of apparatus giving a musical discharge or else by producing, in the circuit for the reception of sustained waves, beats the frequency of which can be adjusted by means of a ticker or similar apparatus.

Into this latter category there enter, and will naturally enter, all kinds of beat-producing devices, and in particular those that are nowadays designated by the name of "heterodynes," with all known or possible arrangements of the connections; since it is sufficient, as indicated in the said main French Patent No. 451614, to substitute the resonance oscillograph for the telephone employed in all arrangements investigated for the reception of sound.

In the reports of the Académie des Sciences for the first half of the year 1914, page 1645, I described an arrangement in which the oscillograph is in circuit with one or more condensers and a self-induction coil forming a resonance circuit. In a patent of addition (No. 19736) to the said French Patent No. 451614, the diagram of Figure 1 shows an arrangement with condensers and an inductance a, b capable of being excited by induction. In the circuit a, b, G , containing the resonance oscillograph the constants may be adjusted by varying the self-induction a, b , or the capacities C^1, C^2 . If

this adjustment is effected in such a way that the electric circuit is in resonance with the beats to be received, this resonance itself effects a selection by reducing the effects produced by the oscillations of other frequencies.

The maximum of sensitiveness is obtained together with the maximum of power in the selection by putting the electric circuit and the vibrating equipment into resonance at the same time, by means of successive trials. Theory and experiment both show that in this way greater amplification can be obtained than by electrical resonance alone or by mechanical resonance alone; especially if care is taken that the electro-mechanical damping of the vibrating member (by the currents that it induces) is less than the mechanical damping.

Moreover, as soon as one departs very far from resonance the coefficient of reduction of amplitude of the oscillations of frequencies lower or higher than the frequency to which both the electric circuit and the vibrating equipment are tuned, is approximately equal to the product of the coefficients of reduction relative respectively to each of these members alone.

For the application of simple mechanical resonance to reception by wireless telegraphy, all the methods at present in use for the reception of musical waves or for the detection of sustained waves by means of apparatus operating upon the heterodyne beat system are very simply applicable, since all that is necessary is to substitute for the telephone the vibrating galvanometer or oscillograph, and to bring the latter to the desired resonance frequency by varying the tension in the suspension wires or their distance part. Bifilar-suspension oscillographs, with or without a small frame stuck on to the bifilar (or on to a flat spring serving the same purpose) give, according to the length of the suspension, and according to the tension, a whole scale of frequencies, which may go from a few hundreds of vibrations per second for frame apparatus, up to several thousands per second for apparatus without frames.

In order to bring about the double resonance, all that is necessary is to employ arrangements in which the telephone circuit is branched, not directly on to the plate circuit of the detector member (when lamps

and heterodynes are employed), but on to a circuit of low resistance coupled through capacity or through induction with the detection circuit, in such a way as to reduce 5 the damping of the electrical oscillations, which is produced by the resistance in circuit. If the coupling is made through a transformer one has every facility for giving the windings of the latter the most favorable constants.

If the coupling takes place by induction, a condenser is added in series. If the coupling takes place by condenser, a self-induction is added in series. In all cases the 15 capacity and inductance of the circuit are regulated in such a way as to realize the condition of resonance at the desired frequency, and the frequency of the vibrating galvanometer is also adjusted to the same value. 20 This operation may be performed by successive trials. It is advantageous on the one hand to reduce to a minimum the parasitic losses of energy by using divided wires for the induction coils, and for the condensers, dielectrics of minimum hysteresis.

The invention will be now readily understood by reference to the accompanying drawing in which:

Figures 1, 2 and 3 are diagrams of alternative arrangements of circuits embodying the invention while Figs. 1', 2' and 3' are slight variations of each respectively.

In Figs. 1 to 3, A is the aerial, E is the earth, D represents the detecting apparatus 35 and in a general way the group of apparatus which may be added to it (i. e., high and low frequency amplifiers, etc.) and H represents a heterodyne source arranged in any way in the vicinity of the receiving apparatus.

40 From the receiving box proceeds a circuit C—R—L of low resistance traversed by the detected current. On the other hand a tuned galvanometer G, to which are added a resistance R', and inductance L', and a condenser C' (these three accessories being adjustable) is put in relation with the circuit of the detected current either by connection to the ends of the condenser C (connection by capacity) see Fig. 1 or by connection to 45 the ends of the inductance L (inductive connection) see Fig. 2, or by a transformer L—S (see Fig. 3). In the case of Fig. 1 the condensers C and C' may be combined and the diagram shown in Fig. 1' will be obtained. 50 In like manner in the case of 2 and 3 I may combine the inductance of the circuit of detection (see Fig. 2') or with the secondary winding of the transformer (see Fig. 3').

The adjustment of the apparatus consists 60 in obtaining, by successive adjustments on the one hand the tuning of the mechanical movement, and on the other hand the tuning of the electric circuit containing the galva-

nometer to the frequency of the beats to be recorded.

The mechanical adjustment is effected by the tension of the wires of the apparatus, and the damping can be regulated by variation of the tension of the inclosure which 70 encloses the movable outfit. The electric adjustment is effected by variation of the inductance L' and of the capacity C' (together or separately) the variation of the resistance R' permitting of the adjustment of the electromechanical damping (before referred to) 75 to a suitable value. The critical value will generally be chosen. The adjustment which is thus definite permits of obtaining the maximum of amplitude of the oscillations in the minimum of time. The apparatus is thus 80 rendered capable of recording radiotelegraphic signals transmitted at great speed. Such is the new industrial result achieved by the invention.

What I claim and desire to secure by Letters Patent of the United States is:—

1. Recording apparatus for radiotelegraphic signals comprising in combination a detector receiving the action of the aerial, an electric circuit of low resistance connected 90 to the detector, a vibrating galvanometer, an electrically tuned circuit comprising the galvanometer connected to the said circuit of low resistance, the frequency of the galvanometer itself being adjusted so that each 95 symbol recorded comprises a sufficient number of oscillations sufficiently close together and the electrical damping being, on the other hand, regulated so that the tuning may be attained at the end of a very small number 100 of oscillations.

2. Recording apparatus for radiotelegraphic signals comprising in combination a lamp detector receiving the action of the aerial and a heterodyne, an electric circuit 10 of low resistance connected to the detector, a vibrating device comprising a suspension oscillograph provided with several wires the length, tension and damping of which are adjustable, an electric circuit electrically 11 tuned comprising the vibrating device connected to the said circuit of low resistance, by inductance the vibrating device being itself adjusted so that each character recorded comprises a sufficient number of oscillations sufficiently close together and the damping being on the other hand regulated so that the tuning may be attained at the end of a very small number of oscillations.

In testimony whereof I affix my signature 11 in presence of two witnesses.

ANDRÉ EUGÈNE BLONDÉL.
